ELECTRIC CONTROL CIRCUIT

Robert E. Kingsmill, Schenectady, N. Y., assignor
to General Electric Company, a corporation of
New York

Application March 27, 1945, Serial No. 585,100

14 Claims. (Cl. 171—97)

1

My invention relates to electric control circuits and more particularly to improved control circuits for effecting a plurality of circuit controlling operations in timed sequence.

While not limited thereto, my invention is particularly applicable to the control of resistance welding systems in which it is desirable to transmit current to a load circuit intermittently for each weld period in a spot welding operation, or for transmitting a single pulse of predetermined duration for each weld. Many timers have been designed for operations of this character but considerable difficulty has been encountered in securing consistent timing operation regardless of supply line voltage fluctuations. Some of the controls have been unduly complicated considering the number and flexibility of the timing functions that could be performed. Accordingly, it is an important purpose of my invention to provide for timing one or more operations new and improved control circuits which are reasonably simple and which are consistent in operation with supply line voltage fluctuations of considerable magnitude.

It is an object of my invention to provide a new and improved electric control circuit.

It is another object of my invention to provide a new and improved electronic timing circuit.

It is a still further object of my invention to provide for timing a plurality of functions a new and improved electronic circuit which operates consistently independently of supply line voltage fluctuations.

In accordance with the illustrated embodiment of my invention, a plurality of timers, each including an electric discharge device, are employed for energizing electromagnetic relays in accordance with a predetermined time pattern. The anode-cathode circuits of the electric valves and the operating coils of the relays are energized from an unregulated alternating current supply circuit. The circuit of the control members of these electric valves is energized from a regulated direct current bus, the voltage of which is maintained in a suitable manner such as by a regulating gaseous discharge valve having a constant voltage characteristic. With this arrangement, the demand on the direct current system is small even when a large number of timers is employed and the supply of closely regulated direct current voltage is not difficult. In the particular embodiment illustrated, the timer is designed to control the application of pressure and current to the electrodes of a resistance welder, in a sequence which is well known in the art, including

55

2

a squeeze period, an overall weld period during which the welder may be alternately energized and deenergized during heat and cool periods, a hold period during which pressure is maintained on the work and an off period during which the work is released with pressure and current both having been terminated. A particularly effective and simple control is employed for effecting the timing of the heat and cool portions of the weld period.

My invention will be better understood by reference to the following description taken in connection with the accompanying drawings, and its scope will be pointed out in the appended claims.

15 In the drawings, Figs. 1a and 1b considered together as Fig. 1 are a schematic representation of one embodiment of my invention; Fig. 2 indicates the operative condition of various elements of the system illustrated in Fig. 1; and Fig. 3 20 illustrates the operating characteristics of the heat and cool timers of the system of Fig. 1.

Referring now to Fig. 1 of the drawings, I have shown my invention incorporated in a control system for controlling the energization of a load circuit 1 which, in the interest of simplification, has been designated merely as a welder initiating circuit for controlling the application of current to a welding load. The conductors 1 may, for example, correspond to conductors 45 and 46 of the system shown in Bivens application Serial No. 530,136, filed April 8, 1944, and assigned to the assignee of the present invention. The energization of a pressure control circuit, which has been illustrated simply as the operating solenoid 2 of a solenoid valve, may be employed to control the pressure applied to the electrodes of the welder in a manner well understood in the art. The control system includes a supply of alternating current 3 which is connected to energize the primary winding 4 of a transformer 5 having secondary windings 6, 7, 8 and 9. The secondary winding 9 provides an alternating current bus including conductors 10 and 11. The conductor 11 is connected through an initiating switch 12 to a bus 13 which may be grounded. The winding 6, which is provided with a midtap, operates in conjunction with a discharge device 14 to provide a full-wave rectifier system and a supply of direct current voltage. The output of the rectifier is filtered by a series resistor 15 and a shunt capacitor 16 and regulated by a circuit including a resistor 17 connected in series with an electric discharge device 18 of the type having a critical minimum ionization voltage and which operates to draw variable amounts of current

through the resistors 15 and 17 to maintain a constant voltage across the conductors 19 and 20 which are connected to the electrodes of the discharge device 18 and which provide a regulated direct current bus. The direct current voltage of conductor 13, which is also an alternating current supply, is maintained at a voltage between conductors 19 and 20 by voltage dividing resistors 21 and 22. Thus conductors 10 and 13 provide a supply of alternating voltage and conductors 13, 19 and 20 provide a supply of regulated direct current voltage for the energization of the various components of the control system.

In order to effect a plurality of operations in timed sequence in accordance with the desired timed pattern, I provide a plurality of electromagnetic relays 23-27, inclusive, each of which is provided with an operating coil 28 connected in series with the anode-cathode circuits, respectively, of electric discharge devices 29-33, inclusive, and across the alternating current supply conductors 19 and 13. An additional electric valve 34, also energized from the alternating current supply conductors 10 and 13, is provided for controlling electric valve 30. Each of the electric discharge devices 29-34 is preferably of the type employing an ionizable medium, such as a gas or vapor, and each includes an anode 35, a cathode 36, a control member or grid 37 and a shield grid 38. The control member 37 of each of the valves is connected with its cathode through a transient suppressing capacitor 39, and the shield grid of each of the valves 29-33, inclusive, is connected directly with its cathode. Since electric valves 29-33 conduct current during half cycles of voltage of only one polarity, an energy storage circuit in parallel with the operating coils 28 of the electromagnets 23-27 is provided to smooth out the current flow through the coils and, as illustrated, each of the operating coils is shunted by a series circuit including a capacitor 40 and a resistor 41. As illustrated in the drawings, the heater elements associated with the cathodes of electric valve 14 and electric valves 29-33, inclusive, are all connected in parallel and energized by the voltage appearing across conductor 13 and a second conductor 42, this voltage being supplied by the winding 7 of transformer 3.

The circuits for energizing the control members of electric valves 29-33, inclusive, are energized from the regulated source of direct current voltage including conductors 13, 19 and 20 and are in general similar. However, since each control circuit includes the contacts of different relays, in order to effect the desired sequential operation, these circuits will be considered individually. The control member 31 of electric valve 29 is connected to the direct current supply conductor 19 through current limiting grid resistor 43, a charging resistor 44 and a timing capacitor 45. Resistor 44 and timing capacitor 45 are shunted by a range resistor 46 and an adjustable timing resistor 47. Resistor 44 functions to determine the charging rate of capacitor 45 from the voltage of direct current supply conductors 19 and 20 and is connected to the conductor 20 through conductor 48, a normally closed contact 49 of a control relay 50 and conductor 20. In a similar manner, the circuit of the control member of electric valve 31 is connected through a current limiting grid resistor 52, a charging resistor 53, and a timing capacitor 54 to conductor 19. The common terminal of resistors 52 and 53 is connected with the direct current supply

conductor 20 by conductor 55, and a normally closed contact 56 on relay 23. A discharge circuit for timing capacitor 53 is provided by series connected resistors 57, 58 and 59 which are connected in shunt with the capacitor 53 and resistor 54. Resistor 58 is adjustable for adjusting the discharge rate of capacitor 54, and a manually operable switch 60 is arranged to short circuit resistor 57 to change the range of operation of the timer. A second manually operable switch 61 is arranged to shunt both resistors 57 and 58 when in its closed position to effectively connect the control member of electric valve 31 with the direct current line 19 to pick up the relay 25 of the weld timer substantially immediately upon timing out of the squeeze time relay 23 when the system is used for ordinary spot welding. With switch 61 closed, the duration of energization of the load for the spot weld is determined by the operation of the heat timer including electric valve 30 and relay 24. The control member of electric valve 32 of the hold timer is connected to conductor 19 through a current limiting grid resistor 62, charging resistor 63 and timing capacitor 64. The charging circuit for capacitor 64 is completed to the supply conductor 20 through the normally closed contact 65 of relay 26 and a normally closed contact 66 of relay 25. The circuit to the supply conductor 20 may also be completed through a normally open contact 67 of relay 24 which shunts normally closed contact 66 of the relay 25. A discharge circuit for the timing capacitor 64 is provided by a range resistor 68 and an adjustable timing resistor 69 which are connected in series with one another and in shunt with resistor 63 and capacitor 64. In a similar manner, the control member of electric valve 33 is connected with the conductor 19 through a current limiting grid resistor 70, a charging resistor 71 and a timing capacitor 72. The charging circuit of the capacitor 72 is completed to the conductor 20 through conductor 73 and a normally open contact 51 of relay 25. A discharge circuit for the timing capacitor 72 is provided by a range resistor 74 and an adjustable timing resistor 75 connected in series with one another and in shunt with the resistor 71 and timing capacitor 72. A single pole manually operable switch 76 is connected in the anode-cathode circuit of electric valve 33 to disable this timing circuit which is the off-time timer when non-repeat operation is desired.

Electric valves 30 and 34 and associated control circuits function as heat and cool timers, respectively, when the system is operated for pulsation welding. The anode-cathode circuit of the electric valve 30 has been previously described. The control member 37 of this electric valve is controlled in accordance with the voltage on a capacitor 77 which is connected in a charging circuit across the direct current supply conductors 19 and 20. As illustrated in the drawings, one terminal of the capacitor 77 is connected with conductor 19 and the other terminal is connected through resistor 78 and adjustable resistor 79 to an adjustable point on voltage dividing resistor 80 which is connected across the direct current supply lines 19 and 20. The control member of electric valve 30 is connected with the terminal of capacitor 77, remote from line 19, through a current limiting resistor 82. The discharge of capacitor 77 is controlled by electric valve 34 which functions with the capacitor 77 to form a control circuit in the nature of a single tube inverter. The

cathode of electric valve 34 is connected with the same terminal of capacitor 77 as the control member of electric valve 30, while the anode of electric valve 34 is connected to the supply line 19 and the other terminal of capacitor 77 through an inductive reactor 83, conductor 84 and a normally closed contact 85 of relay 25. The operation of the electric valve 34 to control the voltage of capacitor 77 is determined by an energizing circuit for the control member thereof which includes a timing capacitor 86, which is connected across the direct current supply lines 19 and 20, through a charging resistor 87, conductor 88 and a normally open contact 89 of relay 24. A discharge circuit for capacitor 86 is provided by a range resistor 90 and an adjustable timing resistor 91 connected in series with one another and in shunt with the capacitor 86 and resistor 87. In order that the operation of the electric valve 34 may be initiated under the control of the relay 23, the control grid 37 thereof is connected through current limiting grid resistor 92 to the direct current line 20 through a normally closed contact 93 of relay 23 or to the lower terminal of charging resistor 87 through a normally open contact 94 of relay 23. With this arrangement, the grid of electric valve 34 is connected to a negative voltage as long as relay 23 is deenergized and is connected for energization in accordance with the charge on timing capacitor 86 upon energization of relay 23. In order to completely discharge the timing capacitor 86 at the end of the weld interval to insure immediate firing of tube 34 at the end of the squeeze time of the next sequence, I provide a circuit for short circuiting the timing capacitor through resistor 87 and including conductor 95, a normally closed contact 96 on relay 24 and a normally open contact 97 on relay 25. The shield grid 38 of electric valve 30 is connected at a voltage slightly negative with respect to the direct current supply line 19 provided by a voltage divider including resistors 98 and 99 connected in series between conductors 13 and 20. This connection functions to limit the negative voltage to which the lower terminal of capacitor 77 charges through resistors 18 and 79 as will become more apparent from the detailed description of operation of the system which follows in a later part of this specification. Since in operation the cathode of electric valve 34 is at variable potential, the cathode heater is energized by a separate source of heating current provided by transformer winding 8.

As stated earlier in the specification, the control relay 50 controls the initiation of operation of the squeeze timer. This relay 50 is provided with an operating coil 100 which is connected to be energized from the alternating current supply lines 10 and 13 through a circuit including a normally closed contact 101 of relay 26. It will be understood that the alternating current voltage is impressed on conductor 13 by closure of the initiating switch 12 so that the control relay 50 is energized as soon as the initiating switch is closed. In addition to the normally closed contact 49 previously described, the relay 50 is provided with normally open seal-in contacts 102 and normally open control contacts 103 which control the operating coil of the solenoid valve 2 from a source of alternating current 104. Thus pressure is applied to the welding electrodes (not shown) during the interval that the control relay 50 is energized. The relay 27 of the off-time timer includes a normally closed contact 105 connected in the anode-cathode circuit of electric valve 32 which is a part of the hold timer. When

the system is adjusted for repeat operation, relay 27 opens contact 105 to deenergize relay 26 and reclose control relay 50 to reinitiate the sequence of timing operations.

5 A better understanding of my invention may be had by a brief consideration of the operation of the illustrated embodiment thereof. It will be assumed that the transformer 3 is energized, that all of the cathodes are at proper operating temperature, and that manual switches 60 and 61 are open and manual switch 76 is closed. This adjusts the system for pulsation welding with repeat operation as long as initiating switch 12 is retained closed.

13 In Fig. 2, the operative condition of the relays, initiating switch 12, and tube 34 are illustrated for all intervals of the sequence of operations. A solid line indicates that the relay is energized and a dotted line indicates that the timing circuit controlling the relay has been initiated in operation.

25 As soon as switch 12 is closed, the operating coil 100 of relay 50 is energized to close contacts 102 and 103 and to open contact 49. Contacts 102 seal in the energizing circuit for the operating coil 100 of relay 50. Contacts 103 energize the operating coil of the solenoid valve 2 to effect the application of pressure to the welding electrodes (not shown). Opening of contact 49 disconnects the capacitor 86 from the direct current line 20 and the lower plate of the timing capacitor discharges through a circuit including resistors 44, 46 and 47. After a predetermined interval of time, the control member of electric 30 valve 29 becomes sufficiently positive to initiate conduction of valve 29 and energize relay 23 to terminate the first interval of the operation or squeeze time during which pressure only is applied to the electrodes.

40 Energization of the relay 23 opens contacts 56 and 93 and closes contact 94. Opening of contact 56 disconnects the timing capacitor 54 of the weld timer from the negative direct current bus 20 to initiate timing of the weld interval. Opening of contact 93 and closure of contact 94 transfers the control grid of electric valve 34 from the negative direct current conductor 20 to the lower terminal of resistor 87. Since capacitor 86 has been maintained discharged, by reason of its charging circuit being open at contact 89 of relay 24 of the heat timer, electric valve 34 is immediately rendered conductive and the capacitor 77, which has previously been charged through a circuit including resistors 78 and 79 to a predetermined voltage, is discharged through the anode-cathode circuit of electric valve 34 and the reactor 83. The reactance in the discharge circuit effects a reversal of voltage of the capacitor 77 so that the lower plate of capacitor 77 is somewhat positive with respect to conductor 19.

45 The operation of this portion of the circuit may be better understood by reference to Fig. 3 in which electric valve 34 and the control circuit associated therewith have been reproduced and the voltages of capacitors 77 and 86 have been plotted as E77 and E86 respectively. On curve 50 E77 condition of electric valve 34 is initiated at point a and terminates at point b. After electric valve 34 has been extinguished at point b, the voltage of capacitor 77 decays on an exponential which is tangential to the voltage determined by the slider on resistor 80. However, when the voltage reaches a value corresponding to the 55 voltage of the common terminal or resistors 98

and 88, the shield grid circuit of electric valve 34 draws current through a circuit including resistors 78 (shown only in Fig. 1) and 79 to maintain the voltage of capacitor 77 substantially constant. As the voltage of the lower terminal of capacitor 77 rises on the curve E77 between points *a* and *b*, the control member of electric valve 30 is raised to a sufficiently positive voltage to render electric valve 30 conductive. Conduction by this valve energizes relay 24 of the heat timer to close the normally open contact 24' in the welder initiating circuit. Operation of relay 24 also closes contact 89 to complete a charging circuit for timing capacitor 86 to charge the lower terminal thereof to the voltage of conductor 20, which is applied to the control element of valve 34, also holds this valve nonconductive after its discharge of capacitor 77. When the voltage of capacitor 77 has decayed along the curve E77 from point *b* to a point indicated at *c*, the electric valve 30 becomes nonconducting and the relay 24 drops out terminating a period or interval of energization of the load circuit by opening contacts 24'.

Deenergization of relay 24 opens contact 89 to initiate a timing operation by timing capacitor 86 which is disconnected from conductor 20 and which discharges through a circuit including resistors 87, 90 (shown only in Fig. 1) and 91. When the voltage of the lower plate of capacitor 86 rises sufficiently to render the control member of electric valve 34 less negative with respect to the cathode than the control voltage, as indicated at point *d*, electric valve 34 is again rendered conducting to discharge the capacitor 77 which applies to the control element of valve 30 the positive voltage value indicated at *e* from which it charges to the point *f* to establish the interval during which electric valve 30 conducts.

In this manner, electric valve 30 is conductive and non-conductive alternately for intervals determined, respectively, by the timing capacitor 77 and its associated circuit and the timing capacitor 86 and its associated circuit. This operation continues for an interval following energization of the relay 23 of the squeeze period timer until energization of the relay 25 of the weld interval timer. When relay 25 picks up at an interval determined by the timing capacitor 54 and its discharge circuit including resistors 53, 51, 58 and 59, contact 85 is opened and contact 97 is closed. Opening of contact 85 interrupts the anode-cathode circuit of electric valve 34 to prevent further discharging of capacitor 77 through this valve and contact 97 establishes a discharge circuit for the timing capacitor 86 after relay 24 drops out closing its control contact 86. Operation of the relay 25 also opens contact 86 to initiate the timing operation of the hold period control including electric valve 32 provided contact 67 of relay 24 is also open. Operation of relay 25 also closes contact 51 to effect the charging of timing capacitor 72 and condition the off-time timer including electric valve 33 for a timing operation by rendering electric valve 33 nonconducting and dropping out relay 27. When initiating switch 12 was closed, contact 51 of relay 25 was open and there was no charge on capacitor 72, so valve 33 became conductive, energizing relay 27.

After an interval of time determined by the discharge of capacitor 64 through resistors 63, 68 and 89, the relay 26 of the hold timer picks up opening contacts 86 and 101. The opening of

contact 101 deenergizes the control relay 50 to reset timing relays 23 and 25 and the opening of contact 65 initiates the timing operation of the off-time timing circuit and maintains valve 33 conductive while the other timing circuits are reset. After the expiration of an interval of time depending upon discharge of capacitor 72 through resistors 71, 74 and 75, and if switch 12 is still depressed, relay 27 of the off-time timer is energized and opens its contacts 105 to drop out relay 26 of the hold-time timer which closes its contacts 101, and the sequence of operations described is reinitiated.

In the foregoing description, the operation of the system for pulsation welding has been considered. If switch 61 is closed, the relay 26 of the weld timer is energized substantially immediately upon operation of relay 23 of the squeeze timer with the resultant opening of its contact 56. With this sequence of operation, the duration of the weld current is established by a single operation of the relay 24 of the heat period timer. The contact 67 of the relay 24 of the heat period timer shunts the contact 86 of the weld interval timer to permit the completion of a full heat period once it is initiated, regardless of energization of the weld interval timer.

From the description of the operation of the control relay 50 earlier in the specification, it is apparent that when the system is adjusted for non-repeat operation by opening manually operable switch 76, it is only necessary to momentarily close the initiating switch 12. As soon as relay 50 is energized and sealed in through its holding contacts 102, the switch 12 may be released and the operation proceeds until the relay 26 of the hold-time timer is energized, dropping out the control relay 50 and locking the system against further operation until subsequent closure of initiating switch 12 again energizes bus 13 from the alternating current source of supply. With the system described, it is believed apparent that the duration of the heat and cool periods may be established independently by adjustment of resistors 79 and 91, respectively, and that the intermittent energization of the load for pulsation welding is effected with a minimum of equipment. Also, by the utilization of separate direct current and alternating current supply lines for the control circuits and anode-cathode circuits, respectively, of a group of cascaded electronic timers, it is possible to provide consistent operation regardless of supply line voltage fluctuations without encountering an unreasonable expense in regulating a direct current bus of large capacity.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. In combination, a source of direct current voltage including means for establishing three points each at a different level of voltage, a resistor and a capacitor connected in parallel and having a common terminal connected to a point of extreme voltage, means including a normally closed initiating switch connecting the other common terminal of said resistor and capacitor to the other point of extreme voltage, an electric

valve including an anode, a cathode and a control member, means connecting the cathode of said electric valve to the point of intermediate voltage, and means connecting said control member for energization in accordance with the voltage of said capacitor.

2. In combination, a source of direct current voltage including means for establishing three points each at a different level of voltage, a resistor and a capacitor connected in parallel and having a common terminal connected to a point of extreme voltage, means including an initiating switch connecting the other common terminal of said resistor and capacitor to the other point of extreme voltage, an electric valve including an anode, a cathode and a control member, means connecting the cathode of said electric valve to said point of intermediate voltage, and means connecting said control member for energization in response to the voltage terminal of said capacitor electrically nearer said initiating switch.

3. In combination, a source of direct current voltage including voltage dividing means for establishing different levels of voltage, an electric valve including an anode, a cathode and a control member, means connecting the cathode of said electric valve for energization in accordance with the voltage of an intermediate point of said voltage dividing means, a resistor and a capacitor connected in parallel and having a common terminal connected to a point of said dividing means which is positive with respect to said intermediate point, means including a normally closed initiating switch connecting the other common terminal of said resistor and capacitor to a point of said dividing means which is negative with respect to said intermediate point, and means connecting said control member for energization in accordance with the voltage of said capacitor.

4. In combination, a source of direct current including three terminals and means for establishing on said terminals three levels of direct current voltage, a source of alternating current, an electric valve including an anode, a cathode and a control member, means connecting one line of said alternating current source with the terminal of intermediate direct current voltage, means connecting the anode-cathode circuit of said electric valve across said alternating current source, a circuit including a resistance and capacitance energized from the remaining terminals of said source of direct current, and means connecting the control member of said electric valve for energization in accordance with the voltage of said capacitance.

5. In combination, a source of direct current including three terminals and means for establishing on said terminals three levels of direct current voltage, a source of alternating current, an electric valve including an anode, a cathode and a control member, means connecting one line of said alternating current source with the terminal of intermediate direct current voltage, means connecting the anode-cathode circuit of said electric valve across said alternating current source, a circuit including a resistance and a capacitance permanently connected with the more positive of the remaining terminals of said source of direct current, means including an initiating control means connecting said resistance and said capacitance with the remaining terminal of said source of direct current, and means connecting the control member of said

electric valve for energization in accordance with the voltage of said capacitance.

6. In combination, a source of direct current including three terminals and means for establishing on said terminals three levels of direct current voltage, a source of alternating current, an electric valve including an anode, a cathode and a control member, means connecting one line of said alternating current source with the terminal of intermediate direct current voltage, means connecting the anode-cathode circuit of said electric valve across said alternating current source, a circuit including a capacitor energized from the remaining terminals of said direct current source, circuit controlling means connected between said capacitor and the more negative of said remaining terminals for controlling the charging of said capacitor from said remaining terminals, a discharge circuit shunting said capacitor, and means connecting the control member of said electric valve for energization in response to the voltage of the terminal of said capacitor electrically nearer said circuit controlling means.

7. In combination, a source of regulated direct current voltage, a source of alternating current voltage, a plurality of electronic timers each including an electric valve having an anode, a cathode and a control member, a plurality of electromagnetic relays each including an operating coil, means connecting the anode-cathode circuit of each of said electric valves in series with the operating coil of a different one of said relays and for energization from said source of alternating current voltage, a timing circuit connected with each of said control members and each comprising a capacitor and charging and discharging circuits therefor, means connecting each of said capacitors for energization from said source of regulated direct current voltage, and means for initiating a transient change in voltage on each of said capacitors in sequence to render the associated electric valves conducting in sequence at intervals determined by said transient voltages.

8. In combination, a source of direct current voltage, a source of alternating current voltage, a plurality of electronic timers each including an electric valve having an anode, a cathode and a control member, a plurality of electromagnetic relays each including an operating coil, means connecting the anode-cathode circuit of each of said electric valves in series with the operating coil of a different one of said relays and for energization from said source of alternating current voltage, a timing circuit connected with each of said control members and comprising a capacitor and a resistor, means normally connecting each of said capacitors for energization from said source of direct current voltage to establish a predetermined charge thereon, means establishing discharge circuits for each of said capacitors, and means interrupting the charging circuits of said capacitors in sequence to render the associated electric valves conducting in sequence at intervals determined by the discharge of the respective capacitors.

9. A timing circuit including a voltage supply circuit, a capacitor, a charging impedance, means connecting said capacitor and said charging impedance in series and for energization from said supply circuit, an electric valve including an anode, a cathode and a control member, means connecting the anode-cathode circuit of said valve in parallel circuit relation with said capaci-

tor so that the voltage of the cathode of said valve is controlled by the voltage of said capacitor, and means for limiting the voltage to which said capacitor charges to a predetermined value which is less than the voltage impressed across said capacitor and charging impedance by said supply circuit.

10. A timing circuit including a voltage supply circuit, a capacitor, a charging impedance, means connecting said capacitor and said charging impedance in series and for energization from said supply circuit, an electric valve including an anode, a cathode and a control member, means connecting the anode-cathode circuit of said valve in parallel circuit relation with said capacitor so that the voltage of the cathode of said valve is controlled by the voltage of said capacitor, and means including a unilaterally conducting path connected between a point of intermediate voltage on said supply circuit and the more negative terminal of said capacitor for limiting the voltage to which said capacitor charges to a value determined by said point of intermediate voltage.

11. A timing control including a voltage supply circuit, a first capacitor, a charging impedance, means connecting said first capacitor and said charging impedance in series and for energization from said supply circuit, an electric valve including an anode, a cathode and a control member, means connecting the anode-cathode circuit of said valve in parallel circuit relation with said capacitor so that the voltage of the cathode of said valve is controlled by the voltage of said capacitor, a timing circuit including a second capacitor for controlling the energization of said control member, means responsive to the voltage of said first capacitor for effecting the connection of said second capacitor across said supply circuit and its disconnection therefrom, and means for limiting the voltage to which said first capacitor charges to a value which is greater than the voltage required for effecting the disconnecting operation of said last mentioned means but less than the voltage impressed across said first capacitor and charging impedance by said supply circuit.

12. A timing control including a direct current voltage supply circuit, a first capacitor, a charging impedance, means connecting said first capacitor and said charging impedance in series and for energization from said supply circuit, an electric valve including an anode, a cathode

and a control member, means connecting the anode-cathode circuit of said valve in parallel circuit relation with said capacitor so that the voltage of the cathode of said valve is controlled by the voltage of said capacitor, a timing circuit including a second capacitor for controlling the energization of said control member, means responsive to the voltage of said first capacitor for initiating a transient voltage change on said second capacitor to vary the voltage of the control member of said electric valve, and means for establishing a voltage to which said first capacitor charges which is independent of the voltage impressed across said first capacitor and charging impedance by said supply circuit.

13. In combination, a source of direct current voltage, a capacitor, a charging circuit for said capacitor including a charging impedance, means for energizing said charging circuit with a variable voltage from said source, an electric valve and inductance means connected in parallel circuit relation with said capacitor, means for rendering said electric valve conducting periodically to discharge said capacitor, and means for limiting the voltage to which said capacitor is charged from said direct current source independently of the voltage impressed on the charging circuit, said means including an electrode of said electric valve and a connection between said electrode and a voltage having a fixed relation with respect to the voltage of said source.

14. In combination, a direct current voltage supply circuit, a capacitor, a charging circuit for said capacitor including a charging impedance, means for energizing said charging circuit with a variable voltage from said supply circuit, an electric valve and inductance means connected in parallel circuit relation with said capacitor so that the cathode voltage of said valve is determined by the voltage of said capacitor, means responsive to the attainment of a predetermined voltage by said capacitor for rendering said electric valve conducting to invert the voltage on said capacitor, and means for limiting the voltage to which said capacitor is charged from said direct current circuit independently of the magnitude of said variable voltage, said means including a unilaterally conducting path connected between said capacitor and a voltage having a fixed relation with respect to the voltage of said supply circuit.
